UNITED STATES PATENT OFFICE.

WARREN B. REED, OF MORGAN CITY, LOUISIANA, ASSIGNOR OF ONE-FOURTH TO J. R. SUMAN, OF HOUSTON, TEXAS, AND ONE-FOURTH TO E. A. PHARR, ONE-EIGHTH TO W. G. REED, AND ONE-EIGHTH TO WALTER HEPLER, ALL OF MORGAN CITY, LOUISIANA.

PROCESS OF AND APPARATUS FOR SETTING CASING AND SCREEN IN WELLS AND CEMENTING.

Application filed March 30, 1922. Serial No. 548,068.

To all whom it may concern:

Be it known that I, WARREN B. REED, a citizen of the United States, residing at Morgan City, parish of St. Mary, Louisiana, have invented a certain new and useful Improvement in a Process of and Apparatus for Setting Casing and Screen in Wells and Cementing, of which the following is a full, clear, and exact description, such as will enable others skilled in the art to which it appertains to make and use the same.

My invention relates to the construction of an improved apparatus for setting screen and casing in wells and cementing same, and also in an improved process to be employed in the setting of the said casing and screen, and cementing the same in the well.

An object of my invention is to provide an efficient process by which means the setting of screen, and casing, and the cementing thereof may be carried out in one continuous operation.

Another object of my invention is to provide an efficient process of setting screen and cementing which will necessitate the employment of but one string of pipe.

Another object is to provide a process of this character in which the screen and casing may be set and cemented in a hole of uniform diameter toward the lower end and in which the top water may be effectively cut off from the screen.

Another object is to provide a process of handling apparatus of this construction whereby the passage of the cement below the casing to the neighborhood of the screen is entirely prevented, and whereby any ascending gas is entirely shut off and thereby prevented from mixing with the liquid cement.

Another object is to construct an apparatus by means of which the setting and cementing operations may be efficiently carried out where no reduction in the diameter of the hole is made above the pay stratum.

Another object is to provide a process and apparatus whereby the screen may be set and tested, and if the pay stratum is not found satisfactory the hole may be deepened and further test made without having to remove screen and packers and thus running the risk of ruining the well.

These and other objects and advantages will more clearly appear in the detailed description which follows:

55

Referring to the drawing herewith, where in like numerals of reference are applied to like parts throughout the different views, Figs. 1 and 2 represent a central longitudinal section through my assembled apparatus 60 showing the parts in position as the apparatus is inserted into the well. Figs. 3 and 4 are broken details showing the apparatus in still different positions. Fig. 5 is a similar broken longitudinal section showing the 65 type of tool employed in removing the wash pipe, and Fig. 6 is a longitudinal section showing the apparatus ready for cementing.

In the use of my device it is understood that the well will be of uniform diameter 70 toward the lower end, the hole being drilled of full size directly into the pay stratum. In this condition of the well, I employ a device such as is disclosed in the drawing. I have, at the lower end of the assembled 75 device, a shoe 1, having a forward flattened blade 2 secured thereto and internally threaded at 3 for attachment to a section of pipe 4 enclosing the wash plug 5. Between the lower end of the pipe 4 and the lower 80 end of the threaded seat 3 in the shoe 1, I secure the usual back-pressure valve 6, of ordinary construction. The wash plug section is secured to the screen 7 by means of a collar or coupling 8.

85

An intermediate liner 9 may be used at option between the screen 7 and the packer 15. I have therefore shown above the screen a section 9 secured by means of a coupling 10 to the said screen. At the upper end of 90 the liner 9 I connect by means of a coupling 11 a second section of liner 12. The coupling 11 is threaded on its inner face for attachment to the two liner sections and forms an attaching means for a threaded plate of 95 brass or other similar material. Said plate has a central opening, also threaded, to form an attachment for the upper end of the wash pipe 14. Thus the plate 13 forms a diaphragm closing the upper end of the liner 9 except for the opening in which the wash pipe is seated. Said wash pipe extends downwardly through the liner and screen and is fitted slidably into the wash plug 5 in the

100

usual manner. Water forced down through said wash pipe will flush the outer side of screen and casing.

The section of liner 12 is especially formed 5 to accommodate the collapsible packer 15 secured thereto. To form a mounting for the said packer the lower end of the liner section is thickened somewhat, providing shoulder 16 against which the lower end 10 of the packer is seated. This packer may be a canvas packer of ordinary construction secured at the lower end by means of windings of wire 17 for attachment to the liner. Spaced somewhat below the upper 15 end of the liner section the pipe is perforated at 18 to allow passage of fluid in the use of my device, as will be later explained. Outside of these openings, and covering the same, is a collar or sleeve 19, 20 secured to the pipe by means of a plurality of small rivets or pins 20. These pins are of brittle construction so that they may be broken when desired. The thickness of the said collar is reduced below the upper end 25 to form an attaching seat for the upper end of the packer which is secured thereto as shown.

The liner above the packer is enlarged 30 slightly in diameter at 21 and threaded with a right hand thread for attachment to a swedged nipple 22. This nipple is slightly larger than the liner and is decreased in diameter at the upper end and threaded at 27 for attachment by means of an ordinary 35 coupling to the casing 28.

In the operation of my improved apparatus the device is assembled as shown in Figs. 1 and 2 and lowered at the end of the casing 28 to the bottom of the well. 40 As the casing is lowered it is filled with water in such manner that when the bottom is reached the screen 7 is washed on the outside by pumping through the casing and the wash pipe 14 a discharge of clear water. 45 After this, the screen is lowered on to the bottom of the hole, the blade 2 securing same against ready rotation. The casing is then rotated in the usual right-hand direction, which serves to unscrew downwardly the joint at 21 and allow the nipple 22 to telescope down over the liner and contact with the upper end of the collar 19. Slack is then given the casing and its 50 weight will serve to break or shear off the pins 20 and cause the packer to expand. In this operation the collar 19 may be driven down into about the position shown in Fig. 4 and the packer will be forced together so as to fill tightly the space between the casing and the wall of the hole. 55 This operation may be assisted by reciprocating the casing so as to exert a tamping action on the packer. After the packer has been thus expanded, the casing is raised to the position shown in Fig. 6 and drilling

fluid is pumped downwardly through the casing and outwardly through the openings 18 in the pipe. It will be noted that a number of these openings have been uncovered by the downward movement of the 70 collar 19. The ability at this stage of the process to obtain circulation of the drilling fluid and also to rotate the casing which has been released from its threaded connection at 21 with the rigidly set screen and packer portion of the apparatus is one of the important features of the process. The casing being freed and circulation being established the pumping and rotating may be continued while preparations are being completed for the process of cementing. 80

The cementing of the casing may be carried out by any one of several approved methods now in common practice. It is 85 possible to cement the casing by what is known as the "plug" method, using one or two plugs as may be desired; or by the various adaptations of the "tube" method.

With the packer set as shown in Fig. 6, 90 and the casing 22 lifted to expose one or more of the holes 18, cement may be pumped directly down through the casing, expelling the drilling fluid therein through the holes 18, and up around the casing to the surface, when the cement column reaches the holes 18 it will follow the same course until as much cement has been placed outside the casing as is desired. The casing may then be rotated to properly distribute the cement around same and prevent the "channelling" 95 thereof. The casing will then be lowered until it rests with full weight upon the collar 19. This lowering of the casing effectually closes the openings 18 and leaves the cement on the outside of the casing in 100 position to set.

A drill stem is then introduced into the casing, lowered to the bottom for the purpose of washing out the remaining cement. 110

If the "tube" method of cementing be employed the drill stem 29 is fitted with a nipple 30 at the lower end thereof, (see Figs. 3 and 4.) Said nipple is provided at its forward end with a tapered plug 31 adapted to seat in the upper end of the wash pipe. Immediately above the plugged lower end, the said nipple is perforated with holes or longitudinal slots 32 through which the cement may find an outlet. When the drill stem and plug are thus lowered to the seat within the upper end of the wash pipe, the drill stem and casing are fitted with a cementing head on the floor of the derrick in the usual manner, and cement is pumped down through the drill stem, through the openings 32 into the casing; flowing upwardly to the openings 18 and is forced outwardly into the space above the packer and outside the casing. The rotating of the casing and the lowering onto the packer is 120 125 130

performed as previously described and the outside cement closed off. Water may then be pumped down through the drill stem to wash out the remaining cement in the drill 5 stem and casing. After the washing is performed the apparatus is allowed to stand until the cement is thoroughly set. It is obvious that whatever method of cementing be employed the packer will effectually close 10 the space above the screen, preventing any cement from settling downward into the pay sands or any gas or fluids from the sands escaping upward into the liquid cement. Furthermore the diaphragm or plate 13 15 with its sealed-in wash pipe 14 and the back pressure valve 6 makes a combined closure which effectually prevents any gas or liquid from entering through the screen to the casing above, making, in this manner, an effective closure for the gases or fluids in the pay sands and avoiding any possibility of the well blowing in prematurely.

When the cement has been properly set 20 the casing may be tested by forcing water downwardly into the casing by full pump pressure. If no liquid escapes upwardly outside of the casing it will be seen that the seal is tight. It is also possible to remove the drill stem and bail out the casing 25 in the usual manner to ascertain whether liquid can find an entrance thereto from the outside. If the cement is found to be properly set and the casing tight, the wash pipe may then be removed.

30 This operation of removing the wash pipe is performed by means of a rotary shoe 33 such as is shown in Fig. 5. This shoe is connected with the lower end of the drill stem and is toothed at its lower end as shown 35 at 34 so that in the rotation thereof the plate 13 will be milled through and the pipe will telescope over the wash pipe. I contemplate providing spring clips 35 or some ordinary overshot device on the interior of 40 the pipe above the shoe so that when the said pipe is withdrawn the clips will engage the remaining portion of the plate about the wash pipe and withdraw the said pipe from the hole. The drill stem in its 45 lowered position may be used to thoroughly wash the interior of the screen before withdrawal.

The screen is thus set ready for a test, 50 and if the well is found to be a producer no further operation will be necessary. If however, the well does not produce and it is desired to drill further, this operation may be performed by introducing the drill down through the casing and the screen so 55 as to cut away the wash plug 5, back pressure valve and the blade 2 and the well then deepened. It will be thus noted that very little danger of ruining the well, as where withdrawal of the screen liners is attempted 60 need be anticipated.

The advantages of this process of cementing a well, wherein the hole is of uniform diameter, will be obvious to one skilled in the art. But one string of pipe will be necessary in setting the screen, and the process of cementing will be made positive and certain. One continuous operation will serve to completely cement and finish the well. My packer will effectively close off 70 the screen from above. There will be no leakage of cement down about the screen and there will be no bubbles of gas finding their way into the cement before the same is properly set. The apparatus is simple in its construction and easily operated. The use of a full-sized hole instead of the usual reduction in size of the hole enables the producer to get the benefit 75 of a full-sized opening in the pay stratum.

Having thus described my invention, the further objects and advantages of which will be apparent without further explanation, what I claim is new and desire to protect by Letters Patent is:

1. In the operation of completing a well, 80 the process of introducing into the hole a casing, wash pipe and screen, washing the screen, setting the screen on the bottom, expanding a packing means above said screen, washing the outside of said casing above 85 the packer, closing said screen from the interior of said casing, cementing the space about said casing above said packing means, lowering said casing onto said packer, 90 washing the interior of said casing, opening 95 said wash pipe, washing said screen and removing said wash pipe.

2. In the operation of completing a well, 100 the process of introducing into the hole a casing, wash pipe and screen, washing the screen, setting the screen on the bottom, closing the space outside said casing above the end of said screen, cementing the hole at the lower end of said casing, washing 105 said screen and removing said wash pipe.

3. The process of completing a well comprising fixing a screen to the casing, introducing the screen into the hole, washing 110 said screen, setting said screen on the bottom of the hole, shutting off the exit for fluid from the screen both outside and inside the casing, cementing the hole around said casing above said screen, washing the casing and opening the passage from the interior of said casing to said screen.

4. The process of completing a well comprising inserting a casing and screen to the bottom of the hole, washing the outside of 115 said screen, setting a packer above said screen outside said casing, cementing the hole above the packer, rotating said casing, washing the interior of the casing.

5. The process of completing a well comprising inserting casing and screen into the 120 hole, setting a packer outside said casing 125

above said screen, cementing around said casing above said packer, and allowing said cement to set.

6. The process of completing a well of uniform diameter comprising lowering casing with screen attached to the bottom of the hole, closing the space above the screen outside said casing, cementing above said closed space, and allowing the cement to set.

10. 7. The process of completing a well of uniform diameter comprising lowering casing and screen to the bottom of the hole, closing the hole above said screen outside and inside said casing, cementing above said screen outside said casing, opening the passage inside said casing to said screen and washing said screen.

8. The process of completing a well comprising lowering a casing with screen attached to the bottom of the hole, cutting off escape of fluid upwardly from around said screen, and then opening the passage from said casing downwardly to said screen.

9. An apparatus of the character described comprising a screen, a wash pipe with wash plate and plug and back pressure valve in combination with a liner secured to said screen, said liner having an exterior outstanding threaded portion adjacent the upper end thereof and perforations below said threaded portion, a casing secured to said liner, a sleeve covering said perfora-

tions, a packer on said liner secured to said sleeve, means to hold said sleeve normally in position and means secured to said threaded portion to release said sleeve and expand said packer.

10. An apparatus of the character described comprising a screen, a wash pipe, wash plate and plug and a back pressure valve in combination with a liner above said screen, a casing formed to telescope over the upper end of said liner and having releasable connection therewith, said liner having perforations therein, a sleeve normally covering said perforations, a packer on said liner secured to said sleeve, said casing being adapted, when disconnected from said liner, to force said collar downwardly, expand said packer, and open said perforations.

11. In an apparatus of the character described, a perforated liner, a sleeve secured detachably thereto, a packer on said liner secured at its upper end to said sleeve, a casing telescoping over said liner and having releasable connection therewith, whereby said casing may act when disconnected from said liner to force said sleeve downwardly and expand said packer.

In testimony whereof, I hereunto affix my signature, this the 25th day of March, A. D. 1922.

WARREN B. REED.
